UNITED STATES PATENT OFFICE.

JULIAN L. PERKINS, OF WEST SPRINGFIELD, AND HIRAM D. CROFT, OF SPRINGFIELD, MASSACHUSETTS, ASSIGNORS, BY MESNE ASSIGNMENTS, TO PERKINS MACHINE AND GEAR COMPANY, OF SPRINGFIELD, MASSACHUSETTS, A CORPORATION OF MASSACHUSETTS.

BROACHING MACHINE.

Application filed January 9, 1926. Serial No. 80,326.

Our invention relates to improvements in machines for cutting, facing off, or machining plain surfaces, such as the longitudinal edges of hinge leaves, for example, and 5 consists generally of a supporting frame having a base of peculiar construction, vertical plungers or rams provided with means for the attachment thereto and adjustment thereon of series or lines of broaches, there 10 preferably being two of these rams which are arranged in counterbalanced relationship, reciprocating and reversing mechanisms for said rams, work-holders, means for securing the work in place in said hold- 15 ers, and mechanisms for operating said work holders to move the work into and out of the cutting field, together with such other parts and members as may be necessary or desirable in order to render the machine complete 20 and serviceable in every respect, all as hereinafter set forth.

The primary object of our invention is to produce a machine, of the class described, wherewith the opposite, plain sides, edges, 25 or surfaces of various objects can be expeditiously and accurately cut or faced.

Another object is to produce such a machine which is comparatively simple both in construction and operation, strong and durable, and not liable to get out of order.

A further object is to provide the machine with rupturable means to prevent breakage of or other injury to the more essential parts of the machine, in the event 35 the chips are permitted to accumulate in too great quantities beneath the rams.

Still another object is to introduce into the operating mechanism for the work holders means to prevent the latter from being 40 either mechanically or manually moved into the broaching field at inopportune times, or at such times as would cause breakage or damage to the broaches or other parts.

Other objects and advantages will appear 45 in the course of the following description.

A preferred form or embodiment of the invention, whereby we attain the objects and secure the advantages of the same, is illustrated in the accompanying drawings, and we will proceed to describe the invention with reference to said drawings, although it is to be understood that the form, construc-

tion, arrangement, etc., of the parts and members in various aspects, are not material, and may be modified without departure from the spirit of the invention.

In the drawings, in which similar reference characters designate similar parts throughout the several views, Figure 1 is a top plan of a broaching machine which 60 embodies a practical form of our invention as aforesaid; Fig. 2, a longitudinal, vertical section through the base of the machine; Fig. 3, a front elevation of said machine; Fig. 4, a left-hand side elevation of 65 the machine; Fig. 5, an enlarged, top plan of one of the rams and the parts and members attached thereto and carried thereby; Fig. 6, an enlarged front elevation of said ram and parts and members, portions being 70 broken away at two places intermediate of the ends; Fig. 7, an enlarged, inner side elevation of said ram, a portion thereof being broken out; Fig. 8, an enlarged, top plan of the mechanism on the left-hand side 75 of the machine for operating the corresponding work holder and the motor reversing mechanism, said work holder being positioned by said mechanism in inoperative position, and the motor-reversing elements 80 in one extreme position; Fig. 9, an enlarged, side elevation of said mechanism; Fig. 10, an enlarged, side elevation of the mechanism illustrated in the preceding view, but disposed to locate the work holder in operative position, and the motor-reversing elements 85 in the other extreme position; Fig. 11, a detail in top plan of certain work-holder stop members; Fig. 12, an enlarged, top plan of one of the work holders; Fig. 90 13, an enlarged, central, vertical section through said holder, taken on the plane of the hand-wheel axis; Fig. 14, an enlarged, front elevation of said work holder, and, Fig. 15, a front elevation of a piece of work 95 the longitudinal edges of which the machine, in the present example, is set up to finish.

The supporting frame of the machine consists generally of a hollow base 1, a superimposed bed 2, the space between said bed and the top of said base being inclosed, and the inclosing walls being considered as parts of the bed, brackets 3-3 extending

laterally from both sides of said bed adjacent to the forward end thereof, a bracket 4 extending laterally from the bed adjacent to the rear end thereof, and a column 5 rising from the bed some distance back from its front end. The rear end portion of the bed 2 is lower than the forward portion thereof, and the brackets 3 are secured to the sides of the higher portion, the column 5 rises from the said higher portion, and the bracket 4 is secured to the left-hand side of the lower portion of said bed.

Covers and doors are provided as usual for the purpose of affording access to the interiors of the base 1 and the bed 2, two of such covers appearing at 6 for the base, and four of such doors appearing at 7, 8, and 9 for the bed. The base 1 extends forwardly beyond the front end of the bed 2, and the covers 6 are over such projecting part, as shown in Figs. 3 and 4, these covers being omitted from Figs. 1 and 2. The doors 7, two in number, are on the front of the bed 2, as shown in Figs. 3 and 4, and the doors 8 and 9 are on the lefthand side of the higher and lower portions, respectively, of said bed, as shown in Fig. 4. There are also doors (not shown) similar to the doors 8 and 9 on the opposite side of the bed.

In addition to the bracket 3, on each side of the bed 2, there are two brackets 10 and 11 secured to such side below said first-named bracket, the bracket 11 being back of the bracket 10.

An electric motor 12, which furnishes the motive power for the machine, is mounted on the bracket 4, and a transmission case 13 is mounted on the lower part of the bed 2. The motor 12 has a shaft 14 with a gear 15 thereon at the right-hand terminal, and said gear intermeshes with a gear 16 on a shaft 17 journaled in the case 13, both of these shafts being transversely arranged relative to the machine. A longitudinal shaft 18 is journaled in suitable bearings in the column 5 and the case 13, and driven from the motor 12, through the medium of the shafts 14 and 17, the gears 15 and 16, and the transmission mechanism in said case. Secured to the forward end of the shaft 18, in front of the column 5, is a gear 19. There is a box 20 on the left-hand bracket 3 at the rear end thereof, for motor-reversing mechanism connected by suitable electrical conductors with the motor 12. This reversing mechanism for the motor is such as is commonly employed for the purpose, and includes a shaft 21 which projects beyond the right-hand side of the box 20, and a gear 22 secured to said shaft on the protruding terminal thereof.

On the front of the column 5, adjacent to the sides thereof, are two vertical T-shaped guides 23 for the same number of plungers or rams 24, said rams having longitudinal channels in their back sides to receive

said guides, and being held in sliding relationship to said guides by means of gibbs 25, in the customary manner. A pair of gibbs 25 is secured to each ram 24 on the back side. Secured to the adjacent sides of the rams 24 are two vertical racks 26 with which the gear 19 intermeshes. Obviously, when the gear 19 is rotated in one direction it acts, through the medium of the racks 26, to carry one of the rams 24 upwardly and the other downwardly, and, when said gear is rotated in the opposite direction, it acts through the same medium to reverse the movements of said rams.

Mounted on top of the column 5, behind the vertical plane in which the guides 23 are located, are two brackets 27, and each of these brackets is provided with an axle 28 on which is mounted a sheave 29. Passing over the sheaths 29 and extending downwardly therefrom is a chain or cable 30. Each end of the cable 30 is secured to the head of a vertical bolt 31 that is received in a lug 32 on the back side of the outer gib 25 secured to one of the rams 24. Each bolt 31 has a nut 33 thereon below the lug 32 through which said bolt extends, whereby means is provided for adjusting the bolt vertically for the purpose of taking up wear, and rendering and keeping the cable 30 taut. Thus means is provided whereby each ram has a counterbalancing effect on the other ram, to the end that the reciprocating movement of said rams is facilitated and stabilized.

Secured to the outer side of each of the rams 24 are upper and under cam plates 34 and 35, respectively. The plate 34, on each ram 24, is secured to said ram near the top thereof, projects rearwardly across the outer edge of the contiguous gib 25, and has a downwardly- and rearwardly-extending flange 36. The plate 35, on each ram 24, is secured to said ram near the bottom and adjacent to the front side thereof, and has an upwardly- and forwardly-projecting flange 37. Each cam plate (34 and 35) is bolted to its ram, and has on the inside face a rib 127, shown in top plan in Fig. 5, that fits into a slot in said ram to assist in holding said plate in place.

The rams 24 move up and down in the spaces in the bed 2 and the base 1, and carry the tools with which the broaching is done, consequently considerable quantities of oil and chips fall into the pits in said base below said rams. These pits are indicated by the numeral 38, in Fig. 2, and each as shown has a floor which inclines upwardly, and rearwardly and forwardly from a central portion which is level. The covers 6 afford access to two compartments 39 below in the front part of the base 1. The floor of each of these compartments at its inner edge forms a junction with the front edge

of the floor of the pit 38 behind and below, and said first-named floor adjacent to said junction is provided with a series of short, upstanding projections or teeth 40, the rear 5 edges of which have the same inclinations and are in the same plane with the upper surface of the forward inclined part of the floor of said pit.

When it is necessary to remove the accumulation of chips from the pits 38, the covers 6 are removed, a suitable implement is inserted first into the open top of one of the compartments 39 and down into the associated pit; and then into the open top 15 of the other compartment 39 and down into the associated pit, and the chips are raked up onto the floors of said compartments, where the teeth 40 prevent them from being washed back into said pits with the oil 20 which drains out of said chips and flows back between said teeth into said pits. Subsequently the chips in the compartments 39 are shoveled out of the top thereof.

A breakable plate 41 is provided beneath each ram 24. Each plate 41 is supported at an incline on the level floor of the pit 38 by means of a rib 42 rising from said floor, said plate having at the rear end a downwardly-extending flange 43 to hook 30 over said lug. The plate 41 at the forward end rests on the floor of the pit 38. The plate 41 is of such dimensions and made of such material that the same can be broken with comparative ease, consequently, in the event the chips be permitted to accumulate in the pit 38 beneath either ram 24 to an extent that would tend to interfere with the movement of said ram, or produce breakage or other damage to the ram and the 35 operating mechanism therefor, said ram in descending operates, through the intervening mass of chips, to cause the plate below to be broken. When the plate 41 breaks, a sound or noise is produced which serves 40 to arouse the attention of the operator, and warns him to stop the machine and remove the excessive accumulation of chips. The 45 breaking of the plate 41 occurs before the accumulation of chips is sufficient to do any serious injury or damage, or even interfere with the proper operation of the ram above.

Extending vertically through the center of each ram 24 is a channel 44 for a hardened, wearing and guide bar 45, which bar is secured by screws or other means to said ram. In the front face of the bar 45 is a longitudinal channel 46 having outwardly-flaring sides and adapted to receive therein 50 a similarly shaped part 47 at the rear end of a female work-holding block 48 which will hereinafter be described. The bar 45 receives the thrust from the block 48, assists in guiding and steadyng the parts 55 during the times said block is in contact

therewith, and is hardened to enable it to withstand the wear incident to the frictional engagement between the bar and block.

On the front of each ram 24, equidistant from the transverse, vertical, central plane of said ram, are broach holders consisting of two inset walls, and forwardly-extending vertical flanges 49—49. These flanges do not extend clear to the top and bottom of the ram 24, and their adjacent, inner faces are parallel with each other, and extend back to the faces of the aforesaid inset walls, with which faces the foremost edge portions of the thrust bar 45 are flush, as clearly shown in Fig. 5. The two-sided abutments or holders thus formed, on each side but forward of the bar 45, are for broaches 50 and securing and adjusting means therefor. In this machine each ram 24 is equipped with eight broaches 50, four on each side of the channel designated at 51, provided between them for the work, and which channel in width is approximately 55 that of the bar 45.

Each broach 50 is secured to its holder, on one side or the other of the work channel 51, after proper adjustment, by means of two bolts 52. Each bolt 52 passes through a transverse slot 53 in the broach 50 into a tapped hole or opening behind the inset face of the holder for said broach. Washers, as 54, may be employed in connection with the bolts 52 for securing the broach in place. The broaches 50 are arranged in parallel sets or lines, end to end in each line, and with the teeth of the broaches in one line adjacent to the teeth of the broaches in the other line. These two rows of teeth define the work channel 51. It is necessary that the lowermost teeth of the broaches 50 in the two lines be farther apart than the uppermost teeth of such broaches, and that the intermediate teeth be on planes connecting said lowermost and uppermost teeth, consequently said broaches must be set to diverge slightly from top to bottom, and it is to permit this to be done that the transverse slot 53 is provided for each bolt 52. The bolts 52 are augmented by abutments or thrust blocks 55—55 in holding the two lines of broaches against upward displacement. The blocks 55 are bolted or otherwise secured to the inset faces of the broach holders immediately above the uppermost broaches 50. Before the bolts 52 are tightened, the broaches 50 are adjusted by means of two pairs of wedges 56 and 57.

One of the wedges 56 is secured by screws or other means against the inner side of each flange 49, with the wide end down. The wedge 56 extends above the top plane of the adjacent thrust block 55, and projecting from the exposed face of such upper 60 65 70 75 80 85 90 95 100 105 110 115 120 125 130 135

portion of said wedge are two lugs 58. One of the wedges 57 is inserted, small end down, between each wedge 56 and the adjacent line of broaches 50, and is adjusted vertically by means of a vertical screw 59. The screw 59 is provided with a cylindrical projection or nut 60 located between the lugs 58, which latter are slotted to enable said screw to be inserted in said lugs through the edges thereof that are parallel with and adjacent to the central, vertical, transverse plane of the ram, with said nut between said lugs and the head of the screw above the upper lug. The screw 59 is tapped into the wedge 57 below, and has a check-nut 61 thereon above the upper lug 58. If, while the check-nut 61 is loose, the screw 59 be rotated in one direction, the wedge 57 with which said screw is in engagement is forced downwardly, and, if said screw be rotated in the opposite direction, said wedge is elevated, these movements on the part of the wedge being due to the fact that the screw is prevented by the nut 60 and the lugs 58 from moving longitudinally. After the wedge 57 has been adjusted to the required extent by its screw 59, the check-nut 61 is tightened on said screw against the top of the upper lug 58 to hold said screw in place against accidental rotation. There must, necessarily, be sufficient clearance between each wedge 57 and the adjacent thrust block 55. The wedges 57 are first adjusted to locate the broaches 50 the proper distance apart to accommodate them to the work, and then the bolts 52 are tightened. Thus the broaches 50 are supported from above by the thrust blocks 55, and at their outer edges by the wedges 57 and 56 and the flanges 49, and are secured against the inset faces of the broach holders by the bolts 52 and washers 54. The wedges should be so proportioned that the lines of broaches 50 in each pair diverge slightly from top to bottom, regardless of the adjustment imparted to them by the wedges 57, being farthest apart at the bottom and nearest together at the top, so that the separation at the bottom is approximately equal to the width of the work to be broached, and the separation at the top is equal to the width of the work after it is broached, that is to say, of the finished work. This machine, as here presented, is adapted to broach the opposite edges of hinge leaves, one of such leaves being represented at 62 in Figs. 12 and 14.

The inclinations of the lines of wedges in each pair are determined by the taper of the wedges 57, while the width of the space between said sets of broaches, or of the work channel 51, is dependent on the position of said wedges vertically. By operating the screws 59 to force the wedges 57 downwardly, the broaches 50 in contact with said wedges are moved closer together, and, by

rotating said screws in the direction to elevate said wedges, said broaches are permitted to be moved farther apart, such adjustments being made while the bolts 52, as well as the check-nuts 61, are loosened. For work narrower than the hinge leaf 62, the broaches 50 in each pair of broach holders must be set nearer together, and, for work which is wider than said leaf, said broaches must be set farther apart. If, for any reason, it be desired to change the inclinations of the broaches 50, wedges having different tapers from the wedges herein shown would have to be substituted for the latter.

It is preferred to employ a plurality of short broaches in a line, rather than one long broach, because the short broaches can be repaired more readily, and they are more economical and generally superior in all respects.

A work-holder is required to cooperate with each of the rams 24, and such holder must be adapted for the easy and quick insertion therein and removal therefrom of the work, and provided with means for easily and quickly securing the work in place and releasing it. These two work holders must also be capable of being thrown into and out of operative position relative to the rams 24, the conditions required being that one holder shall be in operative position while the ram behind it is descending, and at the same time the other holder shall be in inoperative position while the ram behind it is ascending, and vice versa. In the general views the left-hand work holder is shown in its inoperative position and the right-hand work holder is shown in its operative position, the left-hand ram 24 being down and the right-hand ram 24 being up. Referring now especially to Figs. 11, 12, and 13, we will describe the work holder therein illustrated. It is understood that both work holders are alike.

Mounted on and secured to a rock shaft 630 is a carrier 64 extending through which from the front to the back side is a rectangular opening 65. Fitting within the opening 65, and secured therein by means of two bolts 66, is the female clamping block 48. The block 48 is bifurcated to form upper and under arms or extensions, and at the rear end inside is shaped to receive and support the convex side of the hinge leaf 62. The free ends of the clamping-block arms are directed forwardly, the lower arm rests on the bottom of the opening 65, and the bolts 66, which are tapped into and through the top of the carrier 64, are screwed down tightly onto the top of the upper arm. A male clamping block 67 is located in the female block 48, and adapted by location and construction to engage from the front the leaf 62 and hold the same in position in said female block, the rear end of said male block

being shaped to engage the concave side of said leaf. As means for forcing the block 67 tightly against the leaf 62 and withdrawing said block from clamping position, a bearing block 68 and a screw 69 provided with a hand-wheel 70 are employed. In the inner sides at the top and bottom of the female clamping-block arms are two transverse slots 71. The bearing block 68 fits between the arms of the block 48, and on the top and bottom of said bearing block are transverse ribs 72-72 which fits within the slots 71. By this means and in this manner the block 68 is held against displacement either forwardly or rearwardly in the block 48, and said block 68 is held against displacement laterally by the sides of the opening 65. The clamping block 67 is held against lateral displacement by the sides of the opening 65. The screw 69 is tapped into and through the bearing block 68, and has at the rear end an enlargement or nut 73 that is received in a recess 79 in the clamping block 67, such recess being in the center of the front side of said clamping block, whereby the latter is moved forwardly or rearwardly by said nut when said screw is rotated and according to the direction of rotation. At the outer terminal of the screw 69 is a square head 74, and the hand-wheel 70 has a square opening 75 in the hub thereof, which opening is slightly larger than said head. The head 74 is received in the opening 75, and a check-nut 76 is screwed onto a screw-threaded projection 77 at the extreme front end of the screw 69, to retain the hand-wheel 70 in place on said head. The check-nut 76 prevents the hand-wheel 70 from being withdrawn from the head 74 in a forward direction, and a flange 78 on the screw 69 behind said head prevents said hand-wheel from moving rearwardly on said head.

In assembling the parts and members of each work holder, the bearing block 68 is laterally inserted in place in the female clamping block 48, the latter is inserted in the opening 65, the screw 69 is introduced into said bearing block, said clamping block is positioned rearwardly in the carrier 64 far enough to enable the male clamping block 67 to be laterally inserted in said female clamping block, when the nut 73 is received in the opening or slot 79 prepared for the same in said male clamping block, which slot extends through from side to side of the block and opens through the front end thereof, and finally the female clamping block is drawn forward to the required extent in said carrier and secured by means of the bolts 66. It is assumed that the hand-wheel 70 has been mounted on the head 74, and the check-nut 76 screwed onto the projection 77.

When the screw 69 is rotated in one direction, it moves rearwardly or inwardly and

carries with it the male clamping block 67, which slides in the space between the arms of the female clamping block 48, and, when said screw is rotated in the other direction, it moves forwardly or outwardly and carries with it said male block. When the block 67 is moved forwardly by the screw 69 far enough to receive in the space between the back end thereof and the adjacent surface of the block 48 the leaf 62, said leaf is inserted sideways into such space, and then said screw is rotated in the direction to force said block 67 rearwardly into clamping engagement with said leaf. The leaf 62 is, of course, wider than the width of either of the blocks 48 and 67, and must be arranged in said first-named block to project an approximately equal distance on both sides of the same. To release the leaf 62, the screw 69 is rotated in the direction to move forwardly with the block 67. The leaf 62 can now be removed sideways from the block 48.

The opening 75 is made larger than the head 74 for the purpose of enabling a sudden and comparatively powerful impulse or blow to be imparted by the hand-wheel 70, at the end of the rotation thereof in the direction to clamp the work in place, and again at the beginning of the rotation thereof in the direction to release said work. In short, a "hammer" blow is or may be imparted by the hand-wheel at the end of the clamping operation, and again at the beginning of the unclamping operation.

For work of different shapes and sizes, different clamping blocks are required, but otherwise the work holder remains unchanged. Usually it is only the rear end of the male clamping block and the adjacent surface of the female clamping block that have to be changed in order to be accommodated to work of other shapes and sizes.

Each work-holder carrier 64 is provided with a split sleeve 80 which is clamped on to the rock shaft 630 by means of two bolts 81. Upon loosening the bolts 81 the carrier 64 can be adjusted on the rock shaft 630, after which said bolts are again tightened.

There being two work holders which operate independently of each other, there must be two rock shafts 630, and these two shafts are journaled in bearings 82 and 83 on the bed 2 forward of the column 5 and the parts and members supported and carried thereby. The bearings 82 are adjacent to the sides of the bed 2, while the bearings 83 are adjacent to the transverse, vertical, central plane of said bed. There is a bearing 82 and a bearing 83 for each shaft 630, and the former is longer than the latter.

When either work holder is thrown rearwardly into operative position, the rear end 47 of the female clamping block 48 is received in the channel 46 in the thrust bar 45 behind, and said holder comes to rest

against the said bar, and the work or leaf 62 in said block is located below, in, or above, according to the position of the associated ram 24, the passage or channel 51 between the two lines of broaches 50 with which said ram is equipped. At this time the work holder is erect, and when so disposed the portion of the same which is behind the vertical plane of the axis of its rock shaft 630 is considerably heavier than the portion of the same which is in front of said plane. The tendency of the work holder, when in operative position, is, therefore, to gravitate toward the ram 24 behind. When the work holder is thrown forwardly and downwardly into inoperative position, the supporting end 47 of the block 48 and the work are removed entirely from the channel 46 and passage 51. A stop 84, Figs. 3, 9, and 10, is provided for each work holder. These stops are bolted or otherwise secured at their bases to the top of the bed 2 adjacent to the front edge thereof, and extend upwardly and rearwardly into position to be contacted with by the front ends of the carriers 64, when the work holders are swung forward into inoperative position, said carriers then coming to rest directly against the free ends of said stops.

It is necessary to provide mechanism for simultaneously actuating the work holders in opposite directions, so that one work holder is rocked into operative position while the other work holder is rocked out of such position, and vice versa. There must also be provided mechanism for operating the motor-reversing mechanism in the control box 20, each time the rams 24 arrive at the extreme ends of their travel, to reverse the direction of the driving mechanism for said rams, so that when the left-hand ram arrives at its highest point and the right-hand ram arrives at its lowest point, their directions are reversed, and again their directions are reversed when said left-hand ram arrives at its lowest point and said right-hand ram arrives at its highest point. This direction-reversing mechanism is combined with the work-holder-oscillating mechanism on the same side of the machine with the control box 20, it being understood that said last-mentioned mechanism is duplicated on the other side of the machine.

Referring more particularly to Figs. 8, 9, and 10, it will be seen that a rocker arm 85, through the medium of a split hub 86, is mounted on the left-hand, work-holder rock shaft 630 at the outer terminal thereof, said hub being adjustably secured to said shaft by means of a bolt 87. The arm 85 extends downwardly from its shaft 630, and at the lower terminal has a transverse pin or pivot 88. Mounted at its forward terminal on the pin 88 is a link 89 having a downwardly extending part 90 at the rear terminal to form a hook. Also mounted at its forward terminal on the pin 88 is a thrust arm 91, on the outer side of which is a roll 92 loosely mounted on a stud 93 which extends outwardly from said arm near the rear end thereof. The bottom end of the rocker arm 85 is bifurcated, and the forward terminals of the link 89 and the thrust arm 91 are mounted on the pin 88 between the bifurcated parts of said rocker arm. Loosely mounted on the pin 88, outside of the arm 85, is a hub 94 having a downwardly-extending dog 95 and an upwardly-extending finger 96. The arm 85 is provided on the outer side, in front of the upwardly-extending finger 96, with an angular lug 97, and said finger is yieldingly retained in contact with the rear end of said lug, by means of a spring 98 having its ends respectively fastened to the approximately vertical part of said lug and to a pin set in the upper end of said finger. The spring 98 normally retains the dog 95 in position to engage a finger 99 that extends upwardly from the top of a trip 100 into the path of said dog.

The trip 100 has upwardly and rearwardly-extending arms, and is pivotally connected at 101 with the bracket 10 on the left-hand side of the bed 2. In the trip 100 is a notch 102. The notch 102 is located at the base of the finger 99 behind the same, in position to receive a pin 103 which projects outwardly from an approximately horizontal hand lever 104. A spring 105, having its upper and lower ends respectively fastened to the rear end of the rearwardly-extending arm of the trip 100 and to the rear end of a horizontal bolt 106 secured to the bracket 10 below said trip, has a constant tendency to swing said arm downwardly and the finger 99 rearwardly. The lever 104 has its rear terminal pivotally connected at 107 with the bracket 11 which is behind the bracket 10. The front terminal or handle of the lever 104 extends beyond the front of the bed 2 into a convenient position to be grasped by the hand of the operator. A vertical guide plate 108, for the lever 104, is supported from the adjacent side of the bed 2 in position to relieve said lever from lateral strain toward said bed, when said lever is grasped at the front end by the operator standing in front of the machine, and swung upwardly.

Upon the forward movement of the rocker arm 85, the parts being disposed as in Fig. 9, the dog 95 is moved into contact with the upper end of the trip finger 99, and thereby causes the trip 100 to be rocked against the resiliency of its spring 105, because the finger 96 is in contact with the lug 97 and said dog thereby prevented from yielding under the impact of the same with said trip finger. The dog 95 is carried by the arm 85 forwardly, beyond the finger 99, into the position which it occupies in Fig. 10.

When the trip 100 is thus rocked on its pivot 101, the notched part at 102 passes from beneath the pin 103, and the lever 104 is permitted to swing downwardly on its pivot 107, from the position which said lever occupies in Fig. 9, to the position which it occupies in Fig. 100, said pin coming to rest in the angle between the arms of said trip. The trip 100 is held by the pin 103 in the forward position, which said trip is thus caused to assume, until the lever 104 is swung upwardly again, when said trip is caused by the spring 105 to rock rearwardly, until the pin 103 once more enters the notch 102, and the finger 99 is relocated in the path of the dog 95. The roll 92 travels on the lever 104, and, since the rear terminal of the thrust arm 91 is supported by said roll on said lever, said arm swings downwardly on the pin 88 into inoperative position when said lever descends, and when said lever is elevated said arm is again raised into operative position. The arm 91 limits the upward movement of the lever 104. Upon the rearward movement of the arm 85, the dog 95 strikes the finger 99, which has been carried back into the path of said dog, but the contact this time is ineffectual, because the spring 98 yields and permits said dog to snap past said finger. The parts are now and again positioned as in Fig. 9.

Secured to the top of each bracket 3 is a bearing 109, and secured to the top of the bed 2 adjacent to each longitudinal edge thereof is a bearing 110. The axes of the four bearings 109 and 110 are in line with each other. Journaled in each pair of associated bearings 109 and 110 is a horizontal rock shaft 111. Secured on each rock shaft 111, inside of its bearing 110, is a cam-operated rocker arm 112. A shock-absorber 113 has a split collar 114 adjustably mounted on each rock shaft 111 in front of the bearing 110 for such shaft, by means of a bolt 115. Loosely mounted on each rock shaft 111, in front of the shock-absorber 113, is an operating rocker arm 116 for the rocker arm 85 in front. The arm 116 is approximately diametrically opposite to the associated arm 112. The arm 112 has a generally upward direction and the arm 116 a generally downward direction. In addition to these parts and members mounted on each rock shaft 111, there is a reversing rocker arm 117 mounted on the left-hand rock shaft, between the bearing 110 for said shaft and the arm 112 mounted thereon.

Each arm 112 is provided at the upper end with a roll 118 loosely mounted on a stud 119 which projects inwardly from said arm. The roll 118 is in the paths of the flanges 36 and 37 of the cam plates 34 and 35.

Each shock-absorber 113 is provided at each end on opposite sides of its rock shaft 111 with a recessed holder 120 for a spring

121, such holder opening through the bottom. Each rocker arm 116 is provided on opposite edges with lugs 122—122 which extend beneath the adjacent shock-absorber holders 120, to receive the lower ends of the springs 121. The rocking movement imparted to the shaft 111 from the arm 112 is transmitted to the arm 116 through the shock-absorber 113 and the springs 121, instead of being transmitted directly, and undue shock and jar and liability of breakage are thereby avoided. When the arm 112 is rocked rearwardly on and with the shaft 111, it carries with it the shock-absorber 113, and the left-hand spring 121 yieldingly imparts forward movement to the arm 116; and, when said first-named arm is rocked forwardly, yielding rearward movement is imparted to said arm 116, through the medium of the right-hand spring 121.

Each rocker arm 116 is bifurcated at the lower end and provided with a transverse pin 123, and the associated link 89 is hooked over said pin in said bifurcation, the part 90 being behind said pin. The rear end of the arm 91 associated with each arm 116 is adapted to be thrust up under the link 89 in front of the pin 123.

The rocker arm 112, which is associated with the reversing rocker arm 117, is provided on the back edge with upper and under lugs 124 that extend above and below said reversing arm, and carry bolts 125—125. The inner ends of the bolts 125 bear on the upper and under edges of the arm 117, and by means of said bolts the position of said arm relative to the arm 112 may be changed and regulated. At the rear end of the arm 117, is a toothed segment 126 which intermeshes with the reversing-mechanism gear 22, said arm being forward of said gear.

The arrangement, construction, and timing of parts are such that, when the arm 112 is rocked rearwardly, the arm 117 is rocked downwardly and corresponding motion is imparted to the gear 22 by means of the toothed segment 126; and, when said arms are rocked in the opposite directions, said segment imparts motion in the opposite direction to said gear.

The parts and members illustrated in Fig. 9 have just been actuated into the positions which they there occupy by the cam-plate flange 36, at the end of the downward stroke of the left-hand ram 24, and the left-hand work holder has been actuated into inoperative or loading and unloading position. When this ram ascends and approaches the end of its upward travel, the cam-plate flange 37 encounters from the front the roll 118, and actuates the arm 112 rearwardly, with the result that the parts and members of the operating mechanism for the left-hand work holder are caused to assume the positions which they occupy in Fig. 10, and

said work holder is actuated into operative or broaching position. At the same time the reversing arm 117 is swung downwardly to change the direction of the reversing mechanism for the motor. These results are brought about by the rocking motion imparted to the shaft 111 by the arm 112, and through the medium of the shock-absorber 113, and the lugs 124 and bolts 125. 10 The arm 116 in its forward movement carries with it the thrust arm 91 with which the pin 123 is in contact, and said second-named arm imparts a forward movement to the arm 85, and thereby causes the shaft 15 630 to rock and carry the work holder rearwardly into operative position. In moving forwardly with the arm 85, the dog 95 encounters the finger 99 of the trip 100 and releases the pin 103, and the lever 104 swings 20 downwardly and with it the thrust arm 91. As soon as this occurs, or at any time before the ram arrives at the lower end of its travel, the operator grasps the handle of the lever 104 and resets the same and with it 25 the arm 91. It is clear from the foregoing that, by the time the ram arrives at its lowest point, the associated work holder is in inoperative position, and, when such point is reached, the direction of said ram is reversed.

As the left-hand ram 24 approaches the lower end of its travel, the cam-plate flange 36 encounters from behind the roll 118, and causes the arm 112 to be rocked forward until it occupies the position shown in Fig. 9 and the general views. The left-hand ram is now at its lowest point. The arm 112, when actuated by the cam plate 34, imparts an upward movement to the arm 117 and thus brings about a reversal of the motor; and imparts a rearward movement to the arm 116, which movement is transmitted, through the pin 123, the link 89, and the pin 88, to the arm 85, with the result that the 40 right-hand work holder is rocked forwardly into inoperative position. During the rearward movement of the arm 85, the spring 98 yields to permit the dog 95 to snap by the finger 99, provided the arm 104 and the trip 100 have been reset.

As the left-hand ram 24 approaches the upper end of its travel, the cam-plate flange 37 encounters from in front the roll 118, and causes the arm 112 to be rocked rearwardly until it occupies the position shown in Fig. 10. The left-hand ram is now at its highest point. The arm 112, when actuated by the cam plate 35, imparts a downward movement to the arm 117 and thus brings about another reversal of the motor; and imparts a forward movement to the arm 116, which movement is transmitted, through the pin 123, the thrust arm 91, and the pin 88, to the arm 85, with the result 60 65 that the right-hand work holder is rocked

rearwardly into operative position. During this time the dog 95 causes the trip 100 to release the lever 104.

Corresponding operations of the actuating mechanism for the right-hand work holder take place concurrently with those of the actuating mechanism for the left-hand work holder, but in reverse directions, whereby said right-hand work holder is thrown into operative position when said left-hand work holder is thrown out of operative position, and vice versa.

If, for any reason, either lever 104 be not raised to locate the thrust arm 91 supported in part thereon in operative position in front of the associated pin 123, during the time it takes the cooperating ram to ascend, the forward movement imparted to the rocker arm 116 with which said thrust arm is pivotally connected, when the flange 37 of the cam plate 35 on said ram encounters the roll 118 in the path of said flange, is ineffectual so far as the rocker arm 85 on the same side of the machine is concerned, because the pin 123 carried by said arm 116 then rides idly forward beneath the link 89 resting on said pin, and the work holder on that side remains in its inoperative position. The link 89 always operates, however, to rock the arm 85 rearwardly, when said arm is forwardly disposed and the arm 116 is rocked in that direction, that is, rearwardly.

The means just described, whereby free forward movement is permitted to each arm 116, when the associated thrust arm 91 is down in inoperative position, without moving of the arm 85 associated with said arm 116, prevents the work holder operated by said arm 85 from being automatically or mechanically actuated into operative position at the wrong time. And it is desirable, not to say necessary, to supplement the aforesaid preventative means with means to prevent the operator from manually moving the work holder into operative position while the thrust arm 91 is out of engagement with the pin 123. To this end the arm 91 may have an extension 128 in front of the pivot 88, and there may be an abutment 129 on the adjacent side of the bed 2 to cooperate with said extension. The extension 128 is at the front end of the arm 91, and at the front end of said extension is a lug 130, best shown in Fig. 11, that projects inwardly beyond the arm 85, at the lower end, with which arm 85 the thrust arm is pivotally connected, and the abutment 129 is in the path of said lug, when the thrust arm is in inoperative position, but does not project far enough from the bed 2 to interfere with the forward movement of said arm 85. The bottom of the abutment 129 is inclined from the rear end upwardly and forwardly, as represented at 131. 100 105 110 115 120 125 130

The extension 128 with its lug 130 and the abutment 129 are so relatively positioned that, when the thrust arm 91 is in operative position in front of the pin 123, and the arm 85 which supports said thrust arm is rocked forwardly, said lug clears the abutment 129, the lug passing beneath the same; but, when said thrust arm is out of operative position, said extension is disposed with its lug 10 in position behind said abutment to prevent said arm 85 from being swung forwardly, in the event the operator attempts to rock the work holder above into operative position—see dotted-line position of the thrust arm in Fig. 9.

If for any reason the thrust arm 91 be left in inoperative position, as shown in Fig. 10, at the time the flange 36 of the upper cam plate 34 causes the arm 116 to be rocked rearwardly, no harm will result, because then and in that event, as the link 89 carries the arm 85 rearwardly and with it said thrust arm, the lug 130 encounters the inclined bottom 131 of the abutment 129 and rides beneath the same, imparting on the way merely an upward swing to the thrust arm, which then drops down again onto the lever 104.

Assuming that the broaches 50 are secured 30 in place, after proper adjustment, in the broach holders on the rams 24, and that the motor 12 is set in motion, the operation of the machine as a whole is briefly described as follows.

As the right-hand ram 24 descends its broaches 50 cut both of the exposed and protruding, lateral edges of the hinge leaf 62 which is in the right-hand holder, and during the descent of said ram the left-hand ram 24 ascends, and the operator removes the finished hinge leaf 62 from and inserts and fastens an unfinished leaf in the left-hand work holder. At the arrival of the left-hand ram at its highest point and the simultaneous arrival of the right-hand ram at its lowest point, the left-hand work holder is thrown rearwardly into operative position and the right-hand work holder forwardly into inoperative position, and the direction of the gear 19 which drives the rams is reversed, all by the means and in the manner hereinbefore explained in detail. The operator raises the right-hand lever 104, and replaces the finished leaf 62 with 50 an unfinished leaf in the right-hand work holder. Upon the arrival of the left- and the right-hand rams at their lowest and highest points, respectively, their directions are reversed, the left-hand work holder is thrown out and the right-hand work holder is thrown in. The operator raises the left-hand lever 104, and removes the finished leaf 62 from the left-hand work holder and inserts in place thereof an unfinished leaf. 65 And so the operations continue indefinitely.

In the event it be desired to employ this machine for broaching work only on one side, the broach holders on the rams will have attached thereto broaches on the sides only which correspond with those that are to be cut or finished on the work. As examples: Either the left- or right-hand broach holder only on each ram might be equipped with a line of broaches; or the outermost broach holders on the two rams 70 might be so equipped; or the innermost broach holders on the two rams might be equipped. 75

The broach teeth may be shaped to cut grooves in the work, as well as to plane off 80 the same.

What we claim as our invention, and desire to secure by Letters Patent, is—

1. In a broaching machine, vertical reciprocating rams adapted to carry broaches 85 on the sides thereof, and work holders adapted to be moved into and out of operative position relative to and into contact with said sides of said rams, whereby said holders, when in contact with said rams, are partially supported thereby, and position the work in the cutting field, and, when out of said operative position, are unsupported by said rams, and position said work out of 90 said field. 95

2. In a broaching machine, vertical reciprocating rams adapted to carry broaches on the sides thereof, means to actuate said rams simultaneously in opposite directions, and work holders adapted to be moved into and out of operative position relative to and into contact with said sides of said rams, whereby said holders, when in contact with said rams, are partially supported thereby, and position the work in the cutting field, 100 and, when out of said operative position, are unsupported by said rams, and position said work out of said field. 105

3. In a broaching machine, vertical reciprocating rams adapted to carry broaches 110 on the sides thereof, work holders and means simultaneously to actuate said work holders alternately into and out of operative position relative to and into contact with said sides of said rams, whereby said holders, 115 when in contact with said rams, are partially supported thereby, and position the work in the cutting field, and, when out of said operative position, are unsupported by said rams, and position said work out of said field. 120

4. In a broaching machine, vertical reciprocating rams adapted to carry broaches on the sides thereof, means to actuate said rams simultaneously in opposite directions, 125 work holders, and means simultaneously to actuate said work holders alternately into and out of operative position relative to and into contact with said sides of said rams, whereby said holders, when in contact with

said rams, are partially supported thereby, and position the work in the cutting field, and, when out of said operative position, are unsupported by said rams, and position said work out of said field.

5. In a broaching machine, vertically reciprocating rams adapted to carry broaches on the sides thereof, and oscillatory work holders adapted to be rocked into and out of operative position relative to and into contact with said sides of said rams, whereby said holders, when in contact with said rams, are partially supported thereby, and position the work in the cutting field, and, when out of said operative position, are unsupported by said rams, and position said work out of said field.

6. In a broaching machine, vertical rams adapted to carry broaches on the sides thereof, means to actuate said rams simultaneously in opposite directions, oscillatory work holders, and means simultaneously to actuate said work holders alternately into and out of operative position relative to and into contact with said sides of said rams, whereby said holders, when in contact with said rams, are partially supported thereby, and position the work in the cutting field, and, when out of said operative position, are unsupported by said rams, and position said work out of said field.

7. In a broaching machine, constantly reciprocating rams adapted to carry broaches on the sides thereof, oscillatory work holders, and intermittently operating means simultaneously to actuate said work holders into and out of operative position relative to and into contact with said sides of said rams, whereby said holders, when in contact with said rams are partially supported thereby, and position the work in the cutting field, and, when out of operative position, are unsupported by said rams, and position said work out of said field.

45. 8. In a broaching machine, vertical rams adapted to carry broaches on the sides thereof, means to actuate said rams simultaneously in opposite directions, work holders, and means to move one of said work holders into and the other of said work holders out of operative position relative to and into contact with said sides of said rams, each time the rams arrive at the approximate limits of their travel, whereby said holders, when in contact with said rams, are partially supported thereby, and position the work in the cutting field, and, when out of said operative position, are unsupported by said rams, and position said work out of said field.

9. In a broaching machine, a supporting frame having a hollow base, a vertical reciprocating broach-carrying ram supported by said frame and operating in and out of said base, and a breakable member located

in said base beneath said ram, said member being adapted to be broken in the event chips accumulate between said member and said ram to an extent that would be liable to injure the machine or its parts in the absence of the member.

10. In a broaching machine, a supporting frame consisting in part of a hollow base having therein a pit in which is a rib, a breakable plate supported with one edge 75 portion on the floor of said pit, and with the opposite edge portion on said rib, and a reciprocating broach-carrying ram supported by said frame and operating in and out of said base above said plate.

11. In a broaching machine, a vertical reciprocating ram provided with a wearing and guide bar and with broach holders on opposite sides of said bar, means to secure two lines of broaches to and intermediate of 85 the ends of said holders, with a work channel between, and a work holder having a part to bear against said bar and support the work in said channel.

12. In a broaching machine, a vertical reciprocating ram provided with a longitudinally-channelled bar and with broach holders on opposite sides of said bar, means to secure two lines of broaches to and intermediate of the ends of said holders, with 95 a work channel between, and a work holder having a part which is adapted to project into the bar channel and bear against said bar, and a part to support the work in said work channel.

13. In a broaching machine, a vertical reciprocating ram provided on one side with a vertical broach holder, a wedge secured to one side of said holder, a second wedge in contact with the first, means to adjust said 105 second wedge longitudinally, and means to support broaches for adjustment in the direction of their breadth and with their plain longitudinal edges in contact with said second wedge.

14. In a broaching machine, a vertical reciprocating ram provided on one side with a vertical broach holder, a wedge secured to one side of said holder, and provided with lugs, a second wedge to cooperate with the first, a bolt passing through said lugs into threaded engagement with said second wedge, and having an enlargement between said lugs, and means to support broaches for adjustment in the direction of their breadth and with their plain longitudinal edges in contact with said second wedge.

15. In a broaching machine, a vertical reciprocating ram provided on one side with a vertical broach holder, a fixed thrust block secured to said holder in position to receive the upward thrust from a line of broaches below, means to support said broaches for adjustment in the direction of their breadth, and an adjustable wedge be- 125 130

tween one side of said holder and the adjacent edges of said broaches.

16. The combination, in a broaching machine, with a vertical reciprocating ram provided on one side with vertical broach holder, bolts projecting from said holder, a fixed thrust block secured to said holder above said bolts, and wedges supported from said holder, one of said wedges being 10 adjustable, of broaches slotted in the direction of their breadth to receive and be adjustable on said bolts, abutting with their longitudinal plain edges one of said wedges, and held in place from above by said block.
- 15 17. In a broaching machine, a vertical reciprocating ram provided on one side with vertical broach holders spaced apart and equipped with broach-securing means, and a vertical work-holder wearing bar secured 20 to said ram between said broach holders.

18. The combination, in a broaching machine, with a vertical ram provided with a rack and with cam members, and adapted to carry on one side broaches, of a gear 25 intermeshing with said rack, means to drive said gear, a work holder movable toward and away from said ram, and means, operated by said cam members, to actuate said work holder into and out of operative position relative to and into contact with said ram, whereby said holder, when in contact 30 with said ram, is partially supported thereby, and positions the work in the cutting field, and, when out of said operative position, is unsupported by said ram, and positions said work out of said field.

19. The combination, in a broaching machine, with vertical broach-carrying rams provided with racks and upper and lower 40 cam members, and adapted to carry broaches on one side thereof, of a gear intermeshing with said racks, means to drive said gear, reversing means for said driving means, work holders movable toward and 45 away from said rams, means, operated by said cam members, to actuate said work holders into and out of operative position relative to and into contact with said rams whereby said holders, when in contact with 50 said rams, are partially supported thereby, and position the work in the cutting field, and, when out of said operative position, are unsupported by said rams, and position said work out of said field, and means, operated by certain of said cam members, to actuate 55 said reversing means.

20. The combination, in a broaching machine, with a vertical reciprocating broach-carrying ram provided with upper and lower fixed cam members, and adapted to carry on one side broaches, and a work holder movable into and out of operative position relative to and into contact with 60 said ram, whereby said holder, when in con-

tact with said ram, is partially supported 65 thereby, and positions the work in the cutting field, and, when out of said operative position, is unsupported by said ram, and positions said work out of said field, of operating mechanism for said work holder, 70 said mechanism consisting in part of a member which is moved positively by the upper cam member into the path of the lower cam member, and moved positively by the lower cam member into the path of the upper cam 75 member.

21. The combination, in a broaching machine, with a vertical reciprocating broach-carrying ram provided with upper and lower fixed cam members arranged to impart positive movement in opposite directions to a member in the paths of the same, and an oscillatory work holder, of oscillatory mechanism for actuating said work holder, said mechanism having a member in the paths of 80 said cam members.

22. The combination, in a broaching machine, with a vertical broach-carrying ram provided with upper and lower cam members arranged to impart positive movement in opposite directions to a member in the paths of the same, driving means for said ram, reversing means for said driving means, and an oscillatory work holder, of oscillatory mechanism for actuating said reversing 95 means and said work holder, said mechanism having a member in the paths of said cam member.

23. The combination, in a broaching machine, with a vertical reciprocating broach-carrying ram provided with upper and lower fixed cam members arranged to impart positive movements in opposite directions to a member in the paths of the same, a rock shaft, and a work holder secured to said shaft, of a second rock shaft, a rocker arm secured to said last-named shaft, and having a member in the paths of said cam members, and connections between said shafts, whereby the movements imparted by said cam members to said arm is transmitted to said work holder.

24. The combination, in a broaching machine, with a vertical broach-carrying ram provided with upper and lower cam members arranged to impart movements in opposite directions to a member in the paths of the same, means to drive said ram, means to reverse said driving means, a rock shaft, and a work holder secured to said shaft, of a second rock shaft, a rocker arm secured to said second-named shaft, and having a member in the paths of said cam members, connections between said second-named shaft and said reversing means, and connections between said shafts, whereby movement imparted by said cam members to said arm is transmitted through said first-named con-

nections, to said reversing means, and through said second-named connections to said work holder.

25. The combination, in a broaching machine, with a vertical broach-carrying ram provided with upper and lower fixed cam members, motor-driven actuating means for said ram, and a gear forming part of a reversing mechanism for the motor, of a rock shaft, a rocker arm secured to said shaft, and provided with a member in the paths of said cam members the latter being adapted to impart a positive movement in both directions to said rocker-arm member, an arm loosely mounted on said shaft and having a toothed segment inter-meshing with said gear, and means to cause said second-named arm to be operated from said first-named arm.

26. The combination, in a broaching machine, with a vertical broach-carrying ram provided with upper and lower cam members motor-driven actuating means for said ram, and a gear forming part of a reversing mechanism for the motor, of a rock shaft, a rocker arm secured to said shaft and provided with a member in the paths of said cam members, an arm loosely mounted on said shaft, and having a toothed segment intermeshing with said gear, and adjustable means between said arms to enable said second-named arm to be operated from said first-named arm.

27. The combination, in a broaching machine, with a vertical broach-carrying ram provided with upper and lower cam members, motor-driven actuating means for said ram, and a gear forming part of a reversing mechanism for the motor, of a rock shaft, a rocker arm secured to said shaft, and provided with a member in the paths of said cam members, and with lugs, screw-threaded members in said lugs, and an arm loosely mounted on said shaft, and having a toothed segment intermeshing with said gear, said screw-threaded members engaging oppositely-disposed parts of said second-named arm, whereby the latter is adjustably connected with said first-named arm and rocked thereby.

28. The combination, in a broaching machine, with a vertical reciprocating broach-carrying ram provided with upper and lower cam members, of a rock shaft, a rocker arm mounted on said shaft, and having a member in the paths of said cam members, a second rocker arm mounted on and oscillated by said shaft, a second rock shaft, a work holder secured to said second-named shaft, a rocker arm also secured to said second-named shaft, connecting means between said second-named arm and said arm mounted on said second-named shaft, whereby motion in one direction of said second-named arm is imparted to said arm mounted on said second-

named shaft, and trip connecting means between said second-named arm and said arm on said work-holder shaft, whereby a movement in the other direction of said second-named arm is imparted to said arm on said work-holder shaft, when said trip connecting means is operatively disposed.

29. In a broaching machine, a vertical reciprocating broach-carrying ram provided with upper and lower cam members, of oscillatory means having a member in the paths of said cam members, a work holder, oscillatory means therefor, and a connection between said first- and second-named oscillatory means, whereby motion is imparted in one direction from the first to the second, and a trip connection between said first- and second-named oscillatory means whereby motion may be imparted in the opposite direction from the first to the second.

30. In a broaching machine, a vertical reciprocating broach-carrying ram, an oscillatory work holder, and oscillatory operating mechanism therefor, said mechanism consisting in part of an operating arm for said work holder, an operating arm for said first-named arm, and an engaging and disengaging member between said arms which must be manually reset after said work holder has been actuated into inoperative position before it can be actuated into operative position.

31. In a broaching machine, a vertical reciprocating broach-carrying ram, oscillatory mechanism operated by said ram, a work holder, oscillatory operating means for said work holder, a connection between said mechanism and said means to cause said means to move with said mechanism when the latter is actuated in one direction, and to leave said means inoperative when said mechanism is actuated in the opposite direction, and a trip connection between said mechanism and said means to cause said means to move with said mechanism when the latter is actuated in said opposite direction, provided said last-named connection be in operative position.

32. In a broaching machine, a vertical reciprocating broach-carrying ram, oscillatory mechanism operated by said ram, a work holder, oscillatory operating means for said work holder, a connection between said mechanism and said means to cause said means to move with said mechanism when the latter is actuated in one direction, and to leave said means inoperative when said mechanism is actuated in the opposite direction, a second connection between said mechanism and said means to cause said means to move with said mechanism when the latter is actuated in said opposite direction, means to trip said second named connection, and means to reset the same.

33. In a broaching machine, a vertical reciprocating broach-carrying ram, oscillatory mechanism operated by said ram, a work holder, oscillatory operating means for 5 said work holder, a connection between said mechanism and said means to cause said means to move with said mechanism when the latter is actuated in one direction, and to leave said means inoperative when said 10 mechanism is actuated in the opposite direction, a second connection between said mechanism and said means to cause said means to move with said mechanism when the latter is actuated in said opposite direction, automatic means to trip said second-named connection, and means actuated by the operator 15 to reset the same.

34. The combination, in a broaching machine, with a vertical reciprocating broach-carrying ram provided with upper and lower cam members, of a rock shaft, an arm mounted on and secured to said shaft and having a member in the paths of said cam 20 members, a second arm loosely mounted on 25 said shaft, yielding means to connect said second-named arm with said shaft, a work holder, and means, connected with said second-named arm, to actuate said work holder into and out of operative position relative 30 to said ram, said yielding means serving as a shock absorber for said work holder and its operating means.

35. The combination, in a broaching machine, with a vertical reciprocating broach-carrying ram provided with upper and lower cam members, of a rock shaft, a rocker arm secured to said shaft, and having a member in the paths of said cam members, a 35 spring-provided shock absorber secured to said shaft, an arm loosely mounted on said shaft, and having parts against which the shock-absorber springs bear, a work holder, and means, connected with said last-named arm, to actuate said work holder into and 40 out of operative position relative to said ram, said shock absorber protecting from undue jar said work holder.

36. The combination, in a broaching machine, with a vertical reciprocating broach-carrying ram provided with upper and lower fixed cam members, of a rock shaft, a rocker arm mounted on said shaft and having a member in the paths of said cam members, a second rocker arm mounted on said 45 shaft, a second rock shaft, a work holder and a rocker arm mounted on said second-shaft, and a link connecting means between said second-and-last-named arms, whereby the latter is actuated from the former in opposite directions.

37. The combination, in a broaching machine, with a vertical reciprocating broach-carrying ram provided with upper and lower cam members, of a rock shaft, rocker arms mounted on said shaft, one of said

arms having a member in the paths of said cam members, a second rock shaft, a work holder and a rocker arm mounted on said second-named shaft, a link connecting the other of said first-named arms with said last-named arm and adapted to actuate the latter from the former in one direction only, and a thrust arm adapted to be interposed between the link-connected arms to actuate the one from the other in the opposite direction, when said thrust arm is in operative position. 70

38. The combination, in a broaching machine, with a vertical reciprocating broach-carrying ram provided with upper and lower cam members, of a rock shaft, rocker arms mounted on said shaft, one of said arms having a member in the paths of said cam members, a second rock shaft, a work holder and a rocker arm mounted on said second-named shaft, a link connecting the other of said first-named arms with said last-named arm and adapted to actuate the latter from the former in one direction only, a thrust arm adapted to be interposed between the link-connected arms to actuate the one from the other in the opposite direction, when said thrust arm is in operative position, automatic means to release said thrust arm from operative position, and means actuated by the operator to restore said thrust arm to operative position. 80

39. The combination, in a broaching machine, with a vertical reciprocating broach-carrying ram provided with upper and lower cam members, of a rock shaft, a rocker arm mounted on said shaft and having a member in the paths of said cam members, a second rocker arm mounted on said shaft, a second rock shaft, a work holder and a rocker arm mounted on said second-named shaft, and a connection between said second- and last-named arms, for operating the latter from the former arm, said connection comprising a pin projecting from and a link pivotally connected at one end with said first- and second-named arms, respectively, said link having at the opposite end a hook to engage said pin, whereby said last-named arm is actuated from said second-named arm when the same is moved in one direction, and unaffected when the same is moved in the opposite direction. 100

40. The combination, in a broaching machine, with a vertical reciprocating broach-carrying ram provided with upper and lower cam members, of a rock shaft, a rocker arm mounted on said shaft and having a member in the paths of said cam members, a second rocker arm mounted on said shaft, a second rock shaft, a work holder and a rocker arm mounted on said second-named shaft, a link between said second- and last-named arms to cause the latter to be actuated from the former in one direc. 110 115 120 125 130

tion, and a thrust member for said second- and last-named arms, said thrust member being pivoted to one and adapted to be positioned in the path of the other of said second- and last-named arms, respectively, to cause the latter to be actuated from the former into the opposite direction.

41. The combination, in a broaching machine, with a vertical reciprocating broach-carrying ram provided with upper and lower cam members, of a rock shaft, a rocker arm mounted on said shaft and having a member in the paths of said cam members, a second rocker arm mounted on said shaft, and provided with a pin, a second rock shaft, a work holder and a rocker arm mounted on said second-named shaft, a link having one end pivotally connected with said last-named arm and having a hook at the other end to engage said pin, whereby said last-named arm is actuated from said second-named arm when moved in one direction, and a thrust member having one end pivotally connected with said last-named arm, and adapted at the other end to engage said pin, whereby said last-named arm is actuated from said second-named arm when moved in the opposite direction.

42. The combination, in a broaching machine, with a vertical reciprocating broach-carrying ram provided with upper and lower cam members, of a rock shaft, a rocker arm mounted on said shaft and having a member in the paths of said cam members, a second rocker arm mounted on said shaft, a second rock shaft, a work holder and a rocker arm mounted on said second-named shaft, link connecting means between said second- and last-named arms, to cause the latter to be actuated in one direction from the former, a spring-pressed dog carried by said last-named arm, a thrust member pivotally connected with said last-named arm and adapted to be positioned in the path of said arm to cause said last-named arm to be actuated in the opposite direction from said second-named arm, a pivotally-mounted hand lever in supporting position relative to said thrust member, and a spring-pressed trip in supporting relation to said lever, said trip having a part in the path of said dog, whereby said lever permits said thrust member to move into inoperative position, when said trip is actuated by said dog.

43. In a broaching machine, a vertical reciprocating broach-carrying ram provided with upper and lower cam members, a work holder adapted to be actuated into and out of operative position relative to and engagement with said ram, a stop to support and limit the movement of said work holder when actuated into inoperative position, and operating mechanism for said work holder,

said mechanism consisting in part of a member in the paths of said cam members.

44. The combination, in a broaching machine, with a vertical reciprocating broach-carrying ram provided with a longitudinally channeled bar, of an oscillatory work holder comprising a carrier provided with clamping means for the work, said clamping means having at the rear end a projecting part to fit and engage said bar, when said work holder is in operative position, whereby said holder is partially supported by said bar.

45. The combination, in a broaching machine, with a vertical reciprocating broach-carrying ram provided with upper and lower cam members arranged to impart movement in opposite directions to a member in the paths of the same, and a work holder, of mechanism for actuating said work holder into and out of operative position, said mechanism having a member in the paths of said cam members, and trip means adapted, when in inoperative position, to prevent said work holder from being mechanically actuated into operative position.

46. The combination, in a broaching machine, with a vertical reciprocating broach-carrying ram provided with upper and lower cam members arranged to impart movement in opposite directions to a member in the paths of the same, and a work holder, of mechanism for actuating said work holder into and out of operative position, said mechanism having a member in the paths of said cam members, and trip means adapted, when in inoperative position, to prevent said work holder from being manually actuated into operative position.

47. The combination, in a broaching machine, with a vertical reciprocating broach-carrying ram provided with upper and lower cam members arranged to impart movement in opposite directions to a member in the paths of the same, and a work holder, of mechanism for actuating said work holder into and out of operative position, said mechanism having a member in the paths of said cam members, and trip means adapted, when in inoperative position, to prevent said work holder from being mechanically actuated into operative position, and also, when in such position, to prevent said work holder from being manually actuated into operative position.

48. In a broaching machine, a vertical reciprocating broach-carrying ram, oscillatory mechanism operated by said ram, a work holder, oscillatory operating means for said work holder, a connection between said mechanism and said means to cause said means to move with said mechanism when the latter is actuated in one direction, and to leave said means inoperative when said

mechanism is actuated in the opposite direction, a trip connection between said mechanism and said means to cause said means to move with said mechanism when the latter is actuated in said opposite direction, provided said last-named connection be in operative position, and fixed member in the path of said trip connection, when inoperatively disposed, to prevent the same and said means from moving in said opposite direction.

49. In a broaching machine, a vertical reciprocating broach-carrying ram, oscillatory mechanism operated by said ram, a work holder, oscillatory operating means for said work holder, a connection between said mechanism and said means to cause said means to move with said mechanism when the latter is actuated in one direction, and to leave said means inoperative when said mechanism is actuated in the opposite direction, a trip connection between said mechanism and said means to cause said means to move with said mechanism when the latter is actuated in said opposite direction, provided said last-named connection be in operative position, and a fixed member in the path of said trip connection, when inoperatively disposed, to prevent the same and said means from moving in said opposite direction, means to trip said last-named connection, and means to reset the same.

50. The combination, in a broaching machine, with a vertical reciprocating broach-carrying ram, and an abutment, of a rock shaft, a work holder and a rocker arm mounted on said shaft, said arm being adapted to move said work holder into and out of operative position, a member pivotally connected with said arm, means to change the position of said member so that said abutment may be in the path thereof and prevent said arm from moving said work holder into operative position and means to transmit motion to said arm from said ram.

51. The combination, in a broaching ma-

chine, with a vertical reciprocating broach-carrying ram provided with upper and lower cam members, and an abutment, of a rock shaft, rocker arms mounted on said shaft, 50 one of said arms having a member in the paths of said cam members, a second rock shaft, a work holder and a rocker arm mounted on said second-named shaft, a link connecting the other of said first-named arms 55 with said last-named arm and adapted to actuate the latter from the former in one direction only, a thrust arm adapted to be interposed between the link-connected arms to actuate the one from the other in the opposite direction, when said thrust arm is in operative position, said thrust arm having a part in the path of which said abutment projects when the thrust arm is in inoperative position.

52. The combination, in a broaching machine, with a vertical reciprocating broach-carrying ram provided with upper and lower cam members and an abutment, of a rock shaft, rocker arms mounted on said shaft, 70 one of said arms having a member in the paths of said cam members, a second rock shaft, a work holder and a rocker ram mounted on said second-named shaft, a link connecting the other of said first-named arms 75 with said last-named arm and adapted to actuate the latter from the former in one direction only, a thrust arm adapted to be interposed between the link-connected arms to actuate the one from the other in the opposite direction, when said thrust arm is in operative position, said thrust arm having a part into the path of which said abutment projects when the thrust arm is in inoperative 80 position, the abutment being of a character to enable said projecting part to pass the same on the return movement from the extreme limit in said opposite direction of the arm mounted on said second-named shaft.
